US00D887544S

(12) **United States Design Patent** (10) **Patent No.:** **US D887,544 S**
(45) **Date of Patent:** **** Jun. 16, 2020**

(54) **BREATH DETECTOR**

(71) Applicant: **OMRON HEALTHCARE Co., Ltd.**,
Muko (JP)

(72) Inventors: **Kosuke Inoue**, Muko (JP); **Masahiko
Yumoto**, Muko (JP); **Tsuyoshi
Ogihara**, Muko (JP)

(73) Assignee: **OMRON HEALTHCARE Co., Ltd.**
(JP)

(**) Term: **15 Years**

(21) Appl. No.: **29/643,701**

(22) Filed: **Apr. 11, 2018**

(30) **Foreign Application Priority Data**

(57) **CLAIM**

The ornamental design for a breath detector, as shown and described.

DESCRIPTION

FIG. 1 is a perspective view of a breath detector showing our new design;

FIG. 2 is another perspective view thereof;

FIG. 3 is a front view thereof;

FIG. 4 is a rear view thereof;

FIG. 5 is a right side view thereof, the opposite side view being a mirror image;

FIG. 6 is a top view thereof; and,

FIG. 7 is a bottom view thereof.

The broken lines illustrate structure or features which form no part of the claimed design.

1 Claim, 6 Drawing Sheets
